DRY SHAVER HAVING COMBINATION SUCTION AND ADJUSTABLE CUTTING MEANS

Arthur C. McWilliams, Chicago, Ill.

Application June 22, 1955, Serial No. 517,305

7 Claims. (Cl. 30—41.5)

This invention relates to dry shavers, and particularly to improvements in such shavers whereby a closer and more rapid shave is had.

One of the principal objects of the invention is to provide a dry shaver, so constructed that a positive suction action is had against the cutter or shearing head, whereby the hairs protruding from the skin will be caused to be positioned for effective shearing by the cutter head.

Another object is to provide a dry shaver having a positive suction means which will raise the hairs to a position for cutting, which suction means will disperse and dispose of the hair clippings.

Yet another object comprehends the provision of a cutter or shearing head cooperating with a rotating cutter having individual cutter elements rotating in separate orbits so as to provide a more efficient and rapid cutting action.

Still another object is to provide a cutter wherein the rotating cutter elements thereon may be adjusted in their position with respect to the cutter or shearing head, whereby the cutter elements may be readily rehoned or relapped when desired.

Yet another object comprehends the provision of means for adjusting the cutter elements with respect to the cutter or shearing head so as to compensate for wear.

Other objects and important features of the invention will be apparent from a study of the specification following taken with the drawings which together show a preferred embodiment of the invention, and what is now considered to be the best mode of practicing the principles thereof. Other embodiments of the invention may be suggested to those having the benefit of the teachings herein, and such other embodiments are intended to be reserved especially as they fall within the scope of the claims subjoined.

In the drawings:

Fig. 1 is an elevation view of a dry shaver having the improvements according to the present invention embodied therein;

Fig. 2 is a vertical sectional view to an enlarged scale, certain parts being shown in elevation, such section being taken along the line 2—2 of Fig. 1 and looking in the direction of the arrows;

Fig. 3 is an enlarged side elevation view of a cutter adapted for use with the dry shaver shown in Fig. 1;

Fig. 4 is a plan view thereof;

Fig. 5 is a vertical section to an enlarged scale, taken through a coupling member secured to the drive shaft of the motor for operating the dry shaver seen in Figs. 1 and 2;

Fig. 6 is a vertical sectional view through a mating member cooperating with the coupling member seen in Fig. 5;

Fig. 7 is a top plan view of the shearing head for the shaver seen in Figs. 1 and 2; and showing alternate forms of openings in such shearing head;

2

Fig. 8 is a vertical sectional view to an enlarged scale through another form of a shearing head for the dry shaver seen in Figs. 1 and 2;

Fig. 9 is a plan view thereof; and

Fig. 10 is an enlarged vertical sectional view through the shear plate of the shearing head of the shaver seen in Figs. 1 and 2, showing the manner in which hairs extend through the openings therein for shearing by the cutter seen in Figs. 3 and 4.

10 Referring now particularly to Figs. 1 and 2 of the drawings, the improved shaver according to the present invention is referred to generally by the reference numeral 20, and includes a main housing 21 which encloses a driving motor 22, there being an end closure 15 23 for the housing 21 threadably secured thereto as at the mating threads 24. Power leads 26 and 27 extend through an opening 28 formed in the closure member 23 as seen in Fig. 2.

The opposite end of the housing 21 has a flange 29 which is threaded as at 31 to receive a cutter or shearing head 32 having a flange 33 with threads which mate with threads 31 whereby the cutter or shearing head 32 can be threadably secured to the housing 21.

As seen in Fig. 2, the shearing head 32 includes a 25 shearing comb or plate 36 which is generally in the shape of an annulus.

The shearing comb 36 is molded integrally into the cutter head 32, as seen in Fig. 2, the shearing comb 36 having an outer rim 37 which is imbedded in an outer flange 38 of the cutter head 32. The shearing comb 36 also has an inner rim 39 which is imbedded in an inner flange 41, the outer and inner flanges 38 and 41 being thus held together as a unit with a connecting web 34 of the shearing comb 36.

35 The drive motor 22 includes a drive shaft 42 having a coupling member 43, press-fitted thereto. A pair of bayonet pins 44 extend from the coupling 43, and driveably engage a hub 46, said hub having a longitudinal slot 47 therein which is engaged by the bayonet pins 44.

40 The hub 46 is thus driveably connected to the shaft 42 and has press-fitted thereto a cutter assembly indicated generally by the reference numeral 50, see also Figs. 3 and 4. The cutter assembly 50 has a hub 51 which is

45 press-fitted to the hub 46, and a cutter plate 52 is welded or otherwise secured to the hub 51 as at 53. The plate 52 has a plurality of cutter elements 54, 56 and 57 which are bent up from the plane of the plate 52. Each of these cutter elements terminates in blades 58, 59 and 60.

50 These blades are arranged to have different orbital paths as seen in Fig. 4, and are arranged to travel in orbits so as to contact the underside of the shearing comb 36 as seen in Fig. 10, cutter element 58 being shown as a typical one in Fig. 10.

55 As seen in Fig. 1, the shearing head 36 is formed with openings therein through which a hair shaft 62 as seen in Fig. 10 will extend. The precise form of the opening 63 in the shearing comb 36 forms no part of the present invention, and such opening 63 may be in the form of the diamond, or as circular openings 64, or as triangular shape openings 66, all such forms shown in Fig. 7 being by way of illustration only.

The underside of the shearing comb 36 is thus arranged to cooperate with the cutter elements 58, 59 and 61 to 65 shear the hair shafts 62 which extend through the openings 63. The cutter 50 is arranged to provide positive suction against the openings 63 which facilitates the movement of the hair shaft 62 into the openings 63. To this end the plate 52 has extending upward therefrom vanes 67 which alternate with the cutter elements 56.

70 The cutter 50 likewise has blades 68 which extend in the opposite direction from the hub 51, and which to-

gether with the vane 67 serve to sweep air out of a plurality of openings 69 in the housing 21.

Means are provided for adjusting the contact pressure between the cutter elements 58, 59 and 61 with the undersides of the shear comb 36 seen in Fig. 2, and to this end the hub 46 is bored as at 71, the coupling member 43 being likewise bored at 72, the two bores 71 and 72 retaining a spring 73 held therein. The spring 73 urges the cutter 50 against the underside of the shearing comb 36 in a manner well understood.

The hub 46 has a recess 74 in the end thereof remote from the shaft 42, and a ball 76 is arranged to seat in the recess 74. The ball 76 cooperates with an adjusting screw 77 having a concave seat 75 which is threaded into an internally threaded sleeve 78 molded concentrically with the inner flange 41, the adjusting screw 77 having an hexagonal opening 79 therein to receive an adjusting wrench, not shown. The proper deformation may thus be placed upon the spring 73 to adjust the contact pressure of the cutter elements 58, 59 and 61 against the underside of the shearing comb 36. The adjusting screw 77 may be turned to a position so that in its cooperation with the spring 73 the contact pressure of the cutter elements against the shearing comb may be substantially reduced to zero, thereby substantially eliminating any friction therebetween causing heat.

Referring now to Figs. 8 and 9 of the drawings, there is shown another form of a shearing comb referred to generally by the reference numeral 36a. Such a shear comb may be formed of metal mesh 81 which may be placed in a press to flatten the strands 82 making up the mesh 81. The same may also be constructed to provide a generally annular shape cutter head 36a having an outer rim 37a and an inner rim 39a which can be imbedded by a molding process in the outer flange 38 and the inner flange 41 as with the embodiment seen in Fig. 2.

The dry shaver according to the present invention presents a number of advantages not to be found in the shavers of the prior art. One of the important advantages resides in having the cutter elements travel in different orbital paths so as to minimize the heat between such cutter elements and the shearing head. Another advantage resides in the provision of vanes formed integrally with the cutter elements thereby to provide suction to insure that the skin is brought into close contact with the shearing head and to bring the hair shafts into position for shearing. The provision of the vane members also enables the cuttings to be dispersed as fast as they are formed, thereby making it unnecessary to clean the shaver after each use. The constant movement of air through the shearing head and past the cutter elements reduces the heat at the cutter head to a minimum.

Another important advantage resides in the provision of the adjusting screw for varying the pressure between the shear comb and the cutter elements for the purpose of minimizing the heat, and also reducing unwanted wear occasioned by too great a contact pressure between the cutter elements and shear comb.

While the drawings illustrate a shearing head having inner and outer flanges made of moldable material, it is within the skill of one in the art to construct the shearing head entirely of a suitable metal properly formed.

I claim as my invention:

1. In a dry shaver, a housing, a shearing head secured to said housing and arranged to contact the skin, said shearing head including an annular shaped shearing comb with inner and outer rims secured to inner and outer flanges, a drive shaft extending within said housing, a cutter mounted on said shaft for rotation therewith, said cutter having cutter elements mounted thereon and cooperating with said shearing head, said cutter elements being displaced radially from each other so as to rotate in different orbits, vane members disposed on said cutter for creating suction against said shearing head, openings in said housing spaced from said shearing head to disperse

cuttings resulting from the action of said cutter elements and said shearing head, resilient means biasing said cutter in a direction toward said shearing comb, and means for adjusting the position of said cutter with respect to said shearing comb.

2. In a dry shaver, a housing, a shearing head secured to said housing and arranged to contact the skin, said shearing head including an annular shaped shearing comb with inner and outer rims embedded in inner and outer flanges, a drive shaft extending within said housing, a cutter mounted on said shaft for rotation therewith, said cutter having cutter elements mounted thereon and cooperating with said shearing head, said cutter elements being displaced radially from each other so as to rotate in different orbits, resilient means biasing said cutter in a direction toward said shearing comb, and means for adjusting the position of said cutter with respect to said shearing comb.

3. In a dry shaver, a housing, a shearing head secured to said housing and arranged to contact the skin, said shearing head comprising an annular shaped shearing comb, an outer rim embedding the outer rim of said annular shaped shearing comb, an inner rim embedding the inner rim of said annular shaped shearing comb, a drive shaft extending within said housing, a cutter mounted on said shaft for rotation therewith, said cutter having cutter elements mounted thereon and cooperating with said shearing comb, said cutter elements being displaced radially from each other so as to rotate in different orbits, means driven by said shaft for creating suction against said shearing head, and means supported by said inner rim for adjusting the position of said cutter elements with respect to said shearing comb.

4. In a dry shaver, a housing, a shearing head secured to said housing and arranged to contact the skin, said shearing head comprising an annular shaped shearing comb, an outer rim embedding the outer rim of said annular shaped shearing comb, and an inner rim embedding the inner rim of said annular shaped shearing comb, a drive shaft extending within said housing, a cutter mounted on said shaft for rotation therewith, said cutter having cutter elements mounted thereon and cooperating with said shearing head, means driven by said shaft for creating suction against said shearing head, and means for adjusting the position of said cutter elements with respect to said shearing comb comprising a splined connection between said shaft and said cutter, a spring acting between said shaft and said cutter, and an adjusting member threadably held in said inner rim and bearing against said cutter.

5. In a dry shaver, a housing, a shearing head secured to said housing and having a shearing comb arranged to contact the skin, a drive shaft extending within said housing, a cutter mounted on said shaft for rotation therewith, said cutter having cutter elements mounted thereon and cooperating with said shearing head, said cutter elements being displaced radially from each other so as to rotate in different orbits, means driven by said shaft for creating suction against said shearing head, openings in said housing spaced from said shearing head to disperse cuttings resulting from the action of said cutter elements and said shearing head, and means supported on said shearing head for adjusting the position of said cutter elements with respect to said shearing comb.

6. In a dry shaver, a housing, a thin perforated shearing head secured to said housing and arranged to contact the skin, a drive shaft extending within said housing, a cutter mounted on said shaft for rotation therewith, said cutter having cutter elements mounted thereon and cooperating with said shearing head, said cutter elements being displaced radially from each other so as to rotate in different orbits, vane members disposed on said cutter for creating suction against said shearing head, and openings in said housing spaced from said shearing head, to

disperse cuttings resulting from the action of said cutter elements and said shearing head, and means for adjusting the position of said cutter elements with respect to said shearing head.

7. In a dry shaver, a housing, a thin perforated shearing head secured to said housing and arranged to contact the skin, a drive shaft extending within said housing, a cutter mounted on said shaft for rotation therewith, said cutter having cutter elements mounted thereon and co-operating with said shearing head, said cutter elements being displaced radially from each other so as to rotate in different orbits, means driven by said shaft for creating suction against said shearing head, and means for ad-

5 justing the position of said cutter elements with respect to said shearing head.
